MOLTEN METAL SAMPLING TUBE

Rudolph J. Palme, Hamilton, Ontario, Canada, assignor
to Evacuo Enterprises Limited, Hamilton, Ontario,
Canada

Filed Mar. 12, 1971, Ser. No. 123,934

Term of patent 14 years

The portion of the term of the patent subsequent to
May 5, 1984, has been disclaimed

Int. Cl. D24—02

U.S. Cl. D16—1

FIG. 1 is a perspective view of a first embodiment of the molten metal sampling tube embodying my new design; and

FIG. 2 is a perspective view of a second embodiment of the molten metal sampling tube embodying the design.

I claim:

The ornamental design for a molten metal sampling tube, as shown and described.
